Montgomery Patent & Design LLC(57) CLAIM

The ornamental design for a hand washing station for a bathroom, as shown and described.

DESCRIPTION

FIG. 1 is a perspective front view of the hand washing station for bathroom;

FIG. 2 is a front side view thereof;

FIG. 3 is a back side view thereof;

FIG. 4 is a left side view thereof;

FIG. 5 is a right side view thereof;

FIG. 6 is a top side view thereof; and,

FIG. 7 is a bottom side view thereof.

The dashed lines are intended to show boundary areas and form no part of the design thereof.
